CARL JULIUS LAGERHOLM, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS

CIGAR LIGHTER

Application filed December 13, 1928. Serial No. 325,820.

This invention relates to lighters and the like in which a wick is ignited by a shower of sparks projected from pyrophoric metal or other suitable sparking material.

One of the objects of the invention is to provide a simple, durable and compact article of this type which is efficient in action and easily operated. Other objects will be in part obvious and in part pointed out herein-after.

The invention accordingly consists in the features of construction, combinations of elements, and arrangements of parts which will be exemplified in the apparatus hereinafter described and the scope of the application of which will be indicated in the following claims.

In the accompanying drawings, in which is shown one of various possible embodiments of this invention:—

Fig. 1 is an enlarged side elevation partially in section,

Fig. 2 is a vertical section on the line 2—2 of Fig. 1, and

Fig. 3 is a horizontal section on the line 3—3 of Fig. 1.

Similar reference characters refer to similar views throughout the several figures of the drawings.

Referring now to the drawings, there is shown a fuel tank 5 which is adapted to contain the customary filling of absorbent material and liquid fuel. This fuel is poured into the tank through a suitable opening as 4 in the base of the tank in the usual manner.

On the elongated top wall 6 of the fuel tank 5 and adjacent one end thereof is a burner 7 containing a wick 8 extending downwardly for a substantial distance into the tank.

Near its opposite end this top wall is depressed to form a relatively wide cavity 9 from which extends inwardly a narrower cavity or slot 10. The top wall may be formed of cast metal.

A manually operable actuating member 11 is pivotally mounted as at 12 in oppositely disposed webs 13 on the top wall. This member is hollow in form with its under face open. The portion 14 of the member is adapted to swing downwardly into the cavity

9 substantially as indicated in dot in Fig. 1 when such member is manually pressed in the vicinity of 15. This raises the opposite end portion 16 likewise to the position indicated in dot in such figure and within this end portion is formed a snuffer 17 or cap adapted to fit closely over the burner 7. A spring 18 acts between the inner wall of the cavity 9 and the outer end of the portion 15 of the actuating member with its intermediate portion looping the pivot 12 to cause this member to be normally held in the position indicated in solid lines in Fig. 1 with the snuffer 17 pressing on the burner.

The ignition mechanism comprises an abrasive wheel 19, a ratchet 20 secured thereto, a toothed arm 21 and a cylindrical piece of pyrophoric metal 22. The wheel 19 and ratchet 20 are revoluble on a shaft 23 having its ends mounted in the corresponding supports 13. The side walls 25 of the member 11 are slotted as at 25a from their bottom edge upwardly a sufficient distance to permit the member to drop over this shaft 23. The arm 21 is pivotally mounted on a shaft 24 journaled in the opposite side walls 25 of the member 11 and yieldingly pressed against the ratchet 20 by a suitable spring as 26. The pyrophoric metal 22 is slidable in a tube 27 extending through the tank and is inserted into such tube through the usual opening as 28 in the bottom wall 29. This metal is forced against the periphery of the wheel 19 by a suitable spring 30 in such tube. The arm 21 in the normal position of the member 11 projects into the cavity 10 provided to receive it and the lower portion thereof swings therein as such member is actuated to raise the snuffer and ignite the burner.

In the operation of the device the member 11 is manually pressed in the manner described. This swings the portion 16 of this member upwardly to open position, lifting the snuffer from the burner and drawing upwardly the toothed arm 21. The upward movement of the arm 21 causes the ratchet 20 to rotate and to correspondingly rotate the abrasive wheel. The initial movement of the member is relatively slow due to the direction of the pressure relative to the pivot 12.

but as this movement progresses and the snuffer is lifted from the burner an acceleration or what may be called a snap action takes place due to increase of the leverage and this 5 rapid rotation of the wheel causes a shower of sparks to be projected from the pyrophoric metal 22, igniting the burner wick. Upon release of the actuating member, the spring 18 returns this member to its normal or closed 10 position, placing the snuffer on the burner and extinguishing the wick. The form of the teeth on the toothed arm and the yielding pressure of the spring 26 permit this arm to slide over the teeth on the ratchet without 15 causing the ratchet to revolve during the return movement.

From the foregoing description it will be evident that there is provided a device in which the various objects of this invention 20 are achieved and that the same is well adapted to meet the hardest conditions of practical use.

As many possible embodiments may be made of the above invention and as many 25 changes might be made in the embodiment above set forth, it is to be understood that all matter hereinbefore set forth or shown in the accompanying drawings is to be interpreted as illustrative and not in a limiting sense.

30 I claim:

1. In construction for lighters and the like, in combination, a fuel tank having an elongated top wall, a relatively wide cavity formed in said wall adjacent one end thereof 35 of a relatively narrow cavity in said wall extending from said wide cavity toward the opposite end of the wall, a burner on said wall adjacent said opposite end, a manually operable actuating lever member revolvably 40 mounted on a shaft supported by said tank above said top wall and adapted to have one end portion thereof depressed into said wide cavity when said portion is manually pressed, a snuffer at the opposite end of said lever fitting 45 over said burner when said lever is in closed position, an abrasive wheel journaled on said tank adjacent said burner, a ratchet operatively connected to said wheel, a toothed arm pivotally mounted on said lever adjacent 50 said snuffer and projecting into said narrow cavity when said lever is in closed position, said arm being yieldingly held in operative relation with said ratchet, a pyrophoric element co-operating with said wheel, and a 55 spring acting between the under face of said lever and the inner wall of said wide cavity and enveloping the shaft forming the axis of said lever to normally maintain said lever in closed position.

60 2. In construction for lighters and the like, in combination, a fuel tank having a cavity in one wall thereof, a burner on said wall, an abrasive wheel adjacent said burner, a pyrophoric element cooperating with said 65 wheel, a snuffer for said burner, a box-like

manually operable actuating member for said snuffer and said wheel journaled on said tank to swing downwardly into said cavity to cause said snuffer to be raised and said wheel to be rotated, and a spring acting between a well 70 of the cavity and said member to normally maintain said snuffer on said burner, portions of said member forming a housing to substantially enclose said spring, and to substantially close the cavity when in normal 75 position.

3. In construction for lighters and the like, in combination, a fuel tank having a cavity in the top wall thereof, a burner on said wall, an abrasive wheel journaled on said wall adjacent said burner, a pyrophoric element cooperating with said wheel, a manually operable snuffer arm journaled on said tank on an axis relatively remote from said burner and adapted to have a portion thereof 80 swing downwardly into said cavity, a snuffer on said arm, a ratchet wheel operatively connected to said abrasive wheel, and a toothed arm carried by said snuffer arm and yieldingly pressed into engagement with said ratchet wheel to cause said abrasive wheel to be rotated as the snuffer arm is moved to raised position.

4. In construction for lighters and the like, in combination, a fuel tank having a cavity in the top wall thereof, a burner on said wall, an abrasive wheel adjacent said burner, a pyrophoric member cooperating with said wheel, a manually operable member having a finger piece portion which when depressed rotates 95 said wheel to throw sparks on said burner, the depressible portion of said manually operable member being box-like in construction, and guard portions included in said depressible portion so formed as to substantially seal said 100 cavity from foreign matter in all positions thereof, the area of the finger piece portion being substantially the same as the area defined by the guard portions.

5. In construction for lighters and the like, in combination, a fuel tank having an elongated top wall, a burner on said wall, an abrasive wheel journaled near one end of said tank adjacent said burner, a tube extending through said tank and terminating below said 110 abrasive wheel, pyrophoric metal in said tube, a spring in said tube urging said pyrophoric metal into engagement with said wheel a ratchet wheel having peripheral teeth affixed to said abrasive wheel, a snuffer member journaled on an axis located on the other side of said wheel from said burner a portion of which when depressed raises the snuffing part of said member, an arcuate multi-toothed 115 pawl arm journaled on a horizontal axis onto 120 said snuffer member, and means urging the teeth of the pawl arm into contact with the teeth of the ratchet wheel to rotate said wheel when said snuffing portion is raised at a substantially greater angular velocity and 125 130

- through a substantially greater angular distance than and in the same angular direction as said snuffer thereby obtaining a hot spark, the teeth of the pawl arm and the ratchet wheel sliding inoperatively over each other when the snuffing portion descends.
6. In construction for lighters and the like, in combination, a fuel tank having a cavity in one wall thereof, a burner on said wall, an abrasive wheel adjacent said burner, a pyrophoric element cooperating with said wheel, a snuffer for said burner, a box-like manually operable actuating member for said snuffer and said wheel journaled on said tank and substantially at the top of said cavity to swing downwardly into said cavity to cause said snuffer to be raised and said wheel to be rotated, and a spring acting between a wall of the cavity and said member to normally maintain said snuffer on said burner, portions of said member forming a housing to substantially enclose said spring, and to substantially close the cavity when in normal position.
7. In construction for lighters and the like, in combination, a fuel tank having a cavity in the top wall thereof, a burner on said wall, an abrasive wheel journaled on said wall adjacent said burner, a pyrophoric element operating with said wheel, a manually operable snuffer arm journaled on said tank on an axis relatively remote from said burner having a flat topped box-like portion with depending sides and front, a snuffer cap at one end of said flat topped portion and received within the depending sides and front, a portion of said snuffer arm extending the other side of its journal from the snuffer cap and adapted to swing downwardly into said cavity to raise the snuffer cap, a ratchet wheel operatively connected to said abrasive wheel, and a toothed arm carried by said snuffer arm and yieldingly pressed into engagement with said ratchet wheel to cause said abrasive wheel to be rotated as the snuffer arm is moved to raised position.
8. In construction for lighters and the like, in combination, a fuel tank having a cavity in the top wall thereof, a burner on said wall, an abrasive wheel adjacent said burner, a pyrophoric member cooperating with said wheel, a manually operable member having a finger piece portion positioned to be depressed into said cavity and which when depressed rotates said wheel to throw sparks on said burner, the depressible portion of said manually operable member being box-like in construction and guard portions included in said depressible portion so formed as to fit within said cavity and to substantially seal said cavity from foreign matter in all positions thereof, the area of the finger piece portion being substantially the same as the area defined by the guard portions.
9. In construction for lighters and the like,
- in combination, a fuel tank having an elongated top wall and a cavity in said wall extending into the fuel tank, a burner on said wall, a pair of upstanding spaced webs one on each side of said cavity, an abrasive wheel adjacent said burner and rotatably supported by said spaced webs, a pyrophoric element underneath and cooperating with said wheel, a snuffer for said burner, a box-like manually operable actuating member carrying said snuffer at one end thereof and journaled on a shaft extending between said webs and shaped to cover over said cavity and said wheel, unidirectional driving mechanism between said actuating member and said wheel including an arcuate toothed member connected to and moved by said actuating member and extending in one position of said actuating member into said cavity, and a spring acting upon said actuating member to normally maintain said snuffer on said burner and said actuating member in covering position over said wheel.
- In testimony whereof I have signed my name to this specification this fifth day of December, 1928.
- CARL JULIUS LAGERHOLM.
